UNITED STATES PATENT OFFICE.

HERMAN F. BALL, OF NEW YORK, N. Y.

TRUCK FOR RAILROAD-VEHICLES.

1,093,966.

Specification of Letters Patent. Patented Apr. 21, 1914.

Application filed February 18, 1914. Serial No. 818,304.

To all whom it may concern:

Be it known that I, HERMAN F. BALL, of the borough of Manhattan, in the city, county, and State of New York, have invented a certain new and useful Improvement in Trucks for Railroad-Vehicles, of which improvement the following is a specification.

My invention, while more particularly relating to leading trucks for locomotive engines, is equally applicable in railroad rolling stock of other descriptions, and its object is to provide a four wheeled truck, of the "swing" or "lateral motion" type, which shall be of simple and inexpensive construction, of increased lateral stability relatively to those ordinarily heretofore used, and in which the removal and replacement of either pair of wheels may be readily and expeditiously effected when desired.

The improvement claimed is hereinafter fully set forth.

In the accompanying drawings: Figure 1 is a view, the left hand half of which is a side elevation, and the right hand half, a vertical longitudinal central section, of a truck embodying my invention; Fig. 2, a half plan view of the same; Fig. 3, a vertical transverse section, taken in the central plane of one of the axles; and, Fig. 4, a view, the left hand half of which is an end elevation, and the right hand half, a vertical transverse central section.

My invention is herein exemplified in a four wheeled leading engine truck, the frame of which is of the following construction. Two side bars, 1, which are of rectangular section, and made of commercial iron or steel, extend along the sides and top of the truck, and are connected one to the other, at and near their ends, by transversely extending pedestal transoms, 1^a, which are of inverted U section and have pairs of integral pedestal jaws, 1^b, formed on their ends. The pedestal transoms are secured detachably to the side bars by bolts, 1^c, passing through horizontal flanges on the tops of the pedestal jaws and fitted with proper nuts. The side bars are likewise connected, in and adjoining the central transverse plane of the truck, by a swing bearing frame, 1^d, which is secured, at its ends, to the side bars, by bolts, 1^e, and nuts fitted thereon.

The truck wheels, 2, are secured, in the usual manner, on the ends of the truck axles, 2^a, the journals, 2^b, of which, rotate in bear-

ings, 2^c, fitted in axle boxes, 2^d, each of which is adapted to traverse vertically between the members of one of the pairs of pedestal jaws, 1^b. The truck frame is, in this instance, shown as supported on the axle boxes through the intermediation of plate springs, 6, the central bands, 6^a, of which, are fitted in seats on the lower side of the swing bearing frames, 1^d, and which are coupled, at their ends, by links, 6^b, to pairs of equalizers, 7, the ends of which bear on seats on the tops of the axle boxes, 2^d. The spring arrangement does not form part of my present invention, and any other known and preferred design may be substituted for the ordinary construction herein shown and described.

The two inner pedestal jaws, 1^b, on each side of the truck frame, are connected by a tie bar, 3, which, instead of extending to the outer pedestal jaws, as in ordinary practice, is turned upwardly at its ends, and secured to the inner pedestal jaws by bolts, 3^a, and nuts, and, as shown in Figs. 2, 3, and 4, the tie bars, 3, are located in planes on the inner sides of, and entirely clear of, the axle boxes. The inner and outer jaws of each pedestal are connected by a pedestal binder bolt, 3^b, which also passes through the upwardly extending end portion of the adjacent tie bar, 3, and additionally secures it to the inner pedestal jaw, by a nut, 3^c, engaging a thread on the binder bolt, 3^b, and bearing on the tie bar, 3. The binder bolts are provided with nuts, 3^d, bearing on the outer pedestal jaws, and nuts, 3^e, bearing on the inner sides of the inner and outer jaws. By this construction, the axle box cellars, 2^e, may be removed and replaced whenever required, without interference by the tie bars, and it will also be seen that in order to enable either of the axles and its pair of wheels to be dropped, it is only necessary to remove the two binder bolts, 3^b, of its pedestals.

The capacity of lateral motion of the truck frame and its axles and wheels, relatively to the main frame of the locomotive or car on which the truck is applied, is provided for by a swing beam or bolster, 8, which is shown as suspended upon rockers, 9, journaled to vibrate on the swing bearing frame, 1^d, as in the construction set forth in Letters Patent No. 1,060,222, granted and issued to W. E. Woodard, under date of April 29, 1913. The specific form of suspension illustrated does not, however, form

part of my invention, and any other suitable known type may be substituted. A lower center casting, 8^a, is formed at the top of the swing beam and is suitably recessed to receive the usual upper center casting which is connected to the frame of the locomotive or car carried on the truck. A center pin, 8^b, passes through the upper and lower center casting.

10 While I have described and shown a binder bolt as the preferable means of connecting the lower ends of the pedestal jaws of each pair, it will be obvious that a tie bar connected at its ends to the pedestal 15 jaws would constitute the mechanical equivalent of a binder bolt, and may be substituted therefor in the discretion of the constructor.

I claim as my invention and desire to secure by Letters Patent:

1. In a frame for a railroad truck, the combination of two side bars and two pedestal transoms, said transoms having pairs of pedestal jaws formed integral with their 25 ends, and being secured at their ends to the side bars, adjacent to the ends thereof.

2. In a frame for a railroad truck, the combination of two side bars, two pedestal transoms having pairs of pedestal jaws formed integral with their ends, and being secured at their ends to the side bars, adjacent to the ends thereof, and a transverse swing bearing frame secured at its ends to the side bars, intermediate of the pedestal 35 transoms.

3. In a frame for a railroad truck, the combination of two side bars, two pedestal transoms, having pairs of pedestal jaws formed integral with their ends and being

secured at their ends to the side bars, adjacent to the ends thereof, and two tie bars, each extending longitudinally in a plane on the inner sides of the pedestal jaws, and secured at its ends to the pedestal jaws nearer the middle transverse plane of the 45 truck.

4. In a frame for a railroad truck, the combination of two side bars, two pedestal transoms having pairs of pedestal jaws formed integral with their ends and being 50 secured at their ends to the side bars, adjacent to the ends thereof, two tie bars each extending longitudinally in a plane on the inner sides of the pedestal jaws and secured at its ends to the pedestal jaws nearer the 55 middle transverse plane of the truck, and pedestal binder bolts, each connecting the members of a pair of pedestal jaws and also connecting a tie bar to one of said members.

5. In a railroad truck, the combination of two side bars, two pedestal transoms having pairs of pedestal jaws formed integral with their ends and being secured at their ends to the side bars, adjacent to the ends thereof, two tie bars, each extending longitudinally in a plane on the inner sides of the pedestal jaws, and secured at its ends to the pedestal jaws nearer the middle transverse plane of the truck, a transverse swing bearing frame secured at its ends to the side 70 bars, intermediate of the pedestal transoms, a swing beam suspended on said bearing frame, and axle boxes fitted in the several pairs of pedestal jaws.
